UNITED STATES PATENT OFFICE.

ALBERT E. LONG, OF CHICAGO, ILLINOIS, ASSIGNOR TO STROMBERG ELECTRIC COMPANY, OF CHICAGO, ILLINOIS, A CORPORATION OF ILLINOIS.

TIME-CONTROLLED MECHANISM.

Application filed March 27, 1925. Serial No. 18,659.

My invention relates to time controlled mechanism and more particularly to time controlled mechanism for controlling a member which is movable back and forth to cause this movable member to be given a step-by-step movement in one direction and to be returned to its original position.

Such a construction is useful in various relations, one of them being in connection with a workman's time recorder, for determining in what position on the card the record will be made. For instance, it may be desirable that on the first day of the week, all of the records will be made in the first column; that on the second day of the week all the records will be made in the second column; and so forth; and that at the end of the week, the mechanism will be returned to its original position, so that the cards will again be printed in the first column.

Again, it may be desired that during a certain portion of the day, the records shall be made on the cards in the first column; during a succeeding portion of the day in the second column; during still another succeeding portion of the day in the third column, etc., and that at the end of the day the mechanism be again reset to its original position, so that on the following day during the first part of the day the records will be made in the first column.

The present invention is in the nature of an improvement in connection with the construction disclosed in the copending application of Crook and Long, 627,574. In the Crook and Long application, the return of the type carriage to original position at the end of its step-by-step movement required an appreciable length of time. In some situations it is desirable that this return movement should be effected instantly.

One of the objects of this present invention is to provide for the instant return of the carriage.

A further object of my invention is to provide improved means for insuring correct alignment of the type carriage at the time of printing.

Further objects will appear from the description and claims.

In the drawings, in which an embodiment of my invention is shown

Figure 1 is a front view of the mechanism for controlling the movement of the type carriage;

Fig. 2 is a section on the line 2-2 of Fig. 1; showing the type carriage and the mechanism for controlling its movement;

Fig. 3 is a section on the line 3-3 of Fig. 1; and

Fig. 4 is a front view showing some of the parts of Fig. 1 in a different position.

The construction shown is similar to the construction shown in the Crook and Long application referred to and is substantially identical with part of the construction shown in the application of the Crook and Long, Serial No. 6538, filed February 3, 1925, the similar construction comprising the type wheels and carriage and the type carriage control mechanism.

Type wheels and type carriage.

The type carriage 10 is provided with suitable rollers 11 which travel along the transversely extending guide rods 12. A rack 13 is mounted on the front of the carriage which meshes with a pinion 14 controlled by the carriage shifting mechanism. The type carriage has a series of type wheels driven from the type wheel gear 15 having indicia for typing the minute, the hour and the day of the week. These type wheels are shifted periodically to bring the proper printing indicia into printing condition, the minute wheel being shifted once per minute, the hour wheel once per hour and the day wheel once per day.

Type carriage control.

The shifting of the type carriage to bring the printing in the proper column on the card is controlled by suitable transmission from the rotatable time controlled cam mechanism.

The mechanism for controlling the movement of the type wheel carriage has provisions whereby the carriage is given a step-by-step movement in one direction and a quick return in the opposite direction automatically. The step-by-step movement can

be so governed that the shift from column to column will take place automatically at practically any desired intervals. The construction whereby this is accomplished is 5 substantially the same as that described in the co-pending application of Crook and Long, Serial Number 627,574, filed March 26th, 1923. It is practically identical with the construction shown in the co-pending 10 application of Crook and Long, Serial Number 6538. However, in the aforesaid Crook and Long application the return of the type carriage required considerable time, probably an hour or more, whereas in the present 15 construction the return of the carriage is effected almost instantly. The periodic step-by-step movement of the carriage from left to right is controlled by a controlling lever 16 pivotally mounted at 17 and the quick 20 return is effected by means of a lever 18 also pivotally mounted at 17 and engaging the cam 19. This second cam lever effects the 25 return by engaging the first cam lever and moving it, the second cam lever being provided with a projection 20 which engages a pin 21 on the first lever on its return movement. The controlling lever 16 acts on the type carriage through an intermediate lever 22 connected to the lever 16 by means 30 of a spring 23, this intermediate lever 22 having a segmental gear 24 meshing with a pinion 25, with which pinion rotates the gear 14 meshing with the rack 13 on the type carriage. In the ordinary operation of the 35 recorder, the segmental gear lever 22 moves as a unit with the cam controlled lever 16, the spring connection being provided simply to enable manual adjustment of the type carriage independently of the cam control adjustment. This feature of independent adjustment of the type carriage is substantially 40 the same as that disclosed in the above prior application of Crook and Long, Serial Number 627,570 and is effected by means including the pivoted arm 27 and the link 28 connecting this pivoted arm with the lever 22. The follower end 29 of the cam controlled lever 16 is held in engagement with the adjustable arcuate cam pieces 30 by means of 45 a coil tension spring 31 connecting the two cam controlled levers 16 and 18. The follower 32 of the cam controlled lever 18 is held in engagement with the controlling cam by means of a spring 33 having one end secured to a fixed part of the construction and its other end secured to a pin 34 on this lever. 50 During the greater part of the revolution of the cam 19 the follower 32 rests on the periphery of the cam, but in order to provide for an abrupt definite drop-off to insure instant return of the carriage, an additional follower member 35 is provided in the form of the pin semi-circular in cross section secured to the lever 18 and engageable with the cam 19 to control the return 55

movement of the arm. Referring to Figure 4 the cam is rotating in the direction indicated by the arrow A and will soon disengage the follower 32. However, the arm will not be returned at this time as it will still be held out by the engagement of the semi-circular pin follower 35. However, as the movement of the cam continues it will soon disengage this semi-circular pin also and because of the flattened face of this pin, this disengagement will not be gradual, but will take place instantly and permit an instant return of the arm as soon as the pin drops off the abrupt shoulder. 70

As this pin 35 drops off the abrupt shoulder and the arm 18 moves down until the follower 32 engages the depressed portion of the cam, the follower lever 16 will be forced away from the center of the cam-carrying disk 36 because of the engagement 80 of the extension 20 with the pin 21 on the side of the lever 16. The movement of the lever 18 will be sufficient to lift the follower point 29 high enough to clear the outermost one of the arcuate cam pieces 30 so 85 that on the continued movement of the controller cam, this outermost cam piece 30 will ride under the point of the follower. As the controller cam continues to rotate, the abrupt rise 37 of the cam engages the follower pin 90 32 and forces the lever 18 outwardly, disengaging the extension 20 from the pin 21 on the other follower lever and permitting the point 29 of this other follower lever to engage the arcuate cam piece 30 underneath 95 because of the action of the tension spring 31 connecting the two follower levers. 100

During the continued movement of the controlling cam, the point 29 of the follower lever successfully drops off from the successive arcuate cam pieces 30, causing a shifting of the type carriage at the desired time intervals. These arcuate cam pieces 105 may be adjustable circumferentially in the concentric grooves in the cam carrying disk 36, just as in the prior application referred to. 110

In order to rectify or justify any slight misalignment which may be present in the type carriage at the time the type hammer lever is operated, justifying means are provided comprising a notched star wheel 39 rotatable with the pinion 25 and a tooth 40 mounted on a pivoted arm 41 connected with the hammer lever, this tooth being engageable in one of the notches of the star wheel 115 to accurately position the star wheel to cause the printing to be done in accurate alignment in the column. In order to provide for a full and complete movement of the lever which carries the adjusting tooth and also for a full and complete movement of the actuating hammer, a spring lost motion connection is provided between the two comprising a lever extension 42 pivotally 120

125 130

mounted on the main lever portion and having a stop shoulder 43 for engagement with the main lever portion, which is held thereagainst by means of the spring 44. This 5 pivoted lever extension is connected to the hammer lever by means of a link 45.

The main countershaft 46 is driven from any suitable power device (not shown). The type wheel 15 on the type carriage is 10 driven from the main countershaft by means of a gear 47 mounted on this main counter-shaft, an elongated pinion 48 meshing with this gear and a gear 49 mounted on the type carriage and meshing with the elongated pinion 48 and with the type wheel gear 15, this elongated pinion being of sufficient length so that the gear 49 can slide on it and be in mesh with it in any position to which the laterally shiftable carriage can 15 be moved. This transmission is similar to that shown in Crook and Long application, Serial Number 627,574.

The carriage shift controlling cams are driven from the main countershaft 46 by a 20 transmission including a gear 50 meshing with the elongated pinion 48, a bevel pinion 51 rotatable with the gear 50, a bevel gear 52 meshing with a bevel pinion 51, pinion 53 rotatable with the bevel gear 52, a gear 54 25 meshing with the pinion 53, a pinion 55 rotatable with the gear 54, and a gear 56 meshing with the pinion 55 and mounted on the same shaft 57 on which the carriage controlling cams are mounted.

35 While I have shown but one form of my invention, it is to be understood that I do not desire to limit myself to this particular construction since many changes and modifications may be made therein without departure from the scope of the following 40 claims.

I claim:

1. In a time recorder, a type carriage 45 movable back and forth to print in different columns, and means for causing said carriage to move with a step-by-step movement in one direction and to move quickly in the opposite direction to its initial position, comprising spring actuated means and a cam 50 member for controlling said spring actuated means having a stepped cam portion and a follower engageable with said stepped cam portion for controlling the step-by-step movement, and means tensioned during the 55 step-by-step movement for quickly returning the carriage.

2. In a time recorder, a type carriage 60 movable back and forth to print in different columns, and means for causing said carriage to move with a step-by-step movement in one direction and to move quickly in the opposite direction to its initial position, comprising spring actuated means and a cam 65 member for controlling said spring actuated means having a stepped cam portion and a

follower engageable with said stepped cam portion for controlling the step-by-step movement, and means tensioned during the step-by-step movement, for quickly returning the carriage and follower. 70

3. In a time recorder, a type carriage movable back and forth to print in different columns, and means for causing said carriage to move with a step-by-step movement in one direction and to move quickly in the opposite direction to its initial position, comprising spring actuated means and a cam member for controlling said spring actuated means having a stepped cam portion and a follower engageable with said stepped cam portion for controlling the step-by-step movement, and means tensioned during the step-by-step movement for quickly returning the follower. 75 80

4. In a time recorder, a type carriage movable back and forth to print in different columns, and means for causing said carriage to move with a step-by-step movement in one direction and to move quickly in the opposite direction to its initial position, comprising a cam member having a stepped cam portion and a follower engageable with said stepped cam portion for controlling the step-by-step movement, and means for quickly returning said follower to initial 90 position comprising a second cam member and a second follower movable independently of said first follower and engaging said second cam member. 95

5. In a time recorder, a type carriage 100 movable back and forth to print in different columns, and means for causing said carriage to move with a step-by-step movement in one direction and to move quickly in the opposite direction to its initial position, comprising a rotatable cam member having a stepped cam portion and a follower engageable with said stepped cam portion for controlling the step-by-step movement, and means for quickly returning said follower to initial 105 position comprising a second cam member and a second follower movable independently of said first follower and engaging said second cam member, said followers being pivotally and coaxially 110 mounted. 115

6. In a time recorder, a type carriage 120 movable back and forth to print in different columns, and means for causing said carriage to move with a step-by-step movement in one direction and to move quickly in the opposite direction to its initial position, comprising a cam member having a stepped cam portion and a follower engageable with said stepped cam portion for controlling the step-by-step movement, and means for quickly returning said follower to initial 125 position comprising a second cam member and a second follower movable independently of said first follower and engaging said second 130

- cam member, and a spring acting on said second follower tensioned during the step-by-step movement of the first follower.
7. In a time recorder, a type carriage movable back and forth to print in different columns, and means for causing said carriage to move with a step-by-step movement in one direction and to move quickly in the opposite direction to its initial position, comprising a cam member having a stepped cam portion and a follower engageable with said stepped cam portion for controlling the step-by-step movement, and means for quickly returning said follower to initial position comprising a second cam member and a second follower movable independently of said first follower and engaging said second cam member, and means yieldingly connecting said followers.
8. In a time recorder, a type carriage movable back and forth to print in different columns, and means for causing said carriage to move with a step-by-step movement in one direction and to move quickly in the opposite direction to its initial position, comprising a cam member having a stepped cam portion and a follower engageable with said stepped cam portion for controlling the step-by-step movement, and means for quickly returning said follower to initial position comprising a second cam member and a second follower movable independently of said first follower and engaging said second cam member, and means yieldingly connecting said followers.
9. In a time recorder, a type carriage movable back and forth to print in different columns, and means for causing said carriage to move with a step-by-step movement in one direction and to move quickly in the opposite direction to its initial position, comprising a rotatable cam member having a stepped cam portion and a follower engageable with said stepped cam portion for controlling the step-by-step movement, and means for quickly returning said follower to initial position comprising a second cam member and a second follower movable independently of said first follower and engaging said second cam member, and a spring acting on said second follower tensioned during the step-by-step movement of the first follower, and means yieldingly connecting said followers.
10. In a time recorder, a type carriage movable back and forth to print in different columns, and means for causing said carriage to move with a step-by-step movement in one direction and to move quickly in the opposite direction to its initial position, comprising a cam member having a stepped cam portion and a follower engageable with said stepped cam portion for controlling the step-by-step movement, and means for quickly returning said follower to initial position comprising a second cam member and a second follower movable independently of said first follower and engaging said second cam member, said second cam having an abrupt drop and said followers having interengaging means whereby as said second follower slips off the abrupt drop it will cause a quick return of the first follower.
11. In a time recorder, a type carriage movable back and forth to print in different columns, and means for causing said carriage to move with a step-by-step movement in one direction and to move quickly in the opposite direction to its initial position, comprising a cam member having a stepped cam portion and a follower engageable with said stepped cam portion for controlling the step-by-step movement, and means for quickly returning said follower to initial position comprising a second cam member and a second follower movable independently of said first follower and engaging said second cam member, said second cam having an abrupt drop and said followers having interengaging means whereby as said second follower slips off the abrupt drop it will cause a quick return of the first follower, and a spring acting on said second follower, said second cam having a gradual rise engaged by the second follower during the step-by-step movement of the first follower whereby said spring is tensioned gradually during said step-by-step movement.

In witness whereof, I have hereunto subscribed my name.

ALBERT E. LONG.
